UNITED STATES PATENT OFFICE.

JOHN HAHN, OF LOS ANGELES, CALIFORNIA.

WELL EQUIPMENT

1,268,964.

Specification of Letters Patent. Patented June 11, 1918.

Application filed January 5, 1917. Serial No. 140,717.

To all whom it may concern:

Be it known that I, JOHN HAHN, a citizen of the United States, residing at Los Angeles, in the county of Los Angeles and State of California, have invented a new and useful Well Equipment, of which the following is a specification.

This invention relates to equipment designed to pump oil and other liquid from the earth, and an object of the invention is to effect the pumping and flowing operation with minimum disturbance of the oil in the well.

Violent disturbance of the oil in a well results in several troublesome conditions being established, among these being liability of producing sanding of the well and of the producing strata in the immediate vicinity of the well, emulsifying of the oil, and difficulty of pumping the oil by means of a piston when a piston pump is employed in the well.

Another object is to create a reservoir or reservoirs of oil near the bottom of the well so that there will be at all times considerable hydrostatic pressure outward against the oil in the producing strata in order that operation of the pump piston will not produce excessive suction on the producing strata and thereby allow the hydrostatic pressure in the producing strata to force quantities of loosened sand, shale and the like into the well and thereby cause the pump and pump tubing to be plugged up by the sand.

When there is no pressure maintained from within the well against the oil in the producing strata, the oil and gas, when the pressure is great enough, rush out into the well and upward to the surface of the earth in a well known manner to produce a so-called gusher. Such gushing of the well without any control thereover is very detrimental to the pumping thereof because the velocity of the gas and oil is so great that said gas and oil force immense quantities of loosened sand, shale or other debris into the well and pump tubing and clog them up so that frequent pulling of the pump and tubing is necessary to clean them out.

The difference between the atmosphere pressure at the discharge point of the well and the pressure of oil and gas in the producing strata is so great that when the oil and gas are allowed to freely vent into the

well, and therefrom, when the well is a flowing one, the gas expands so greatly on its way out of the well that the oil is violently agitated thus producing the troublesome conditions noted above. The oil and gas thus relieved so quickly of a large percentage of the pressure foams and said foam, consisting partly of oil and possibly some water, sand, shale and the like, but mainly gas, rises in the pump tubing and if the well is being pumped with a piston pump said foam rises in the pump cylinder. It is clear that when the pump piston is operated it will only be working on a body of foam and consequently a very small volume of oil can be pumped.

A primary object of this invention is to do away with the above described difficulties.

Another object of this invention is to effect the foregoing objects by a comparatively simple and inexpensive construction.

Other objects and advantages will be disclosed in the subjoined detail description.

The accompanying drawings illustrate the invention:

Figure 1 is an elevation mainly in vertical mid section of well equipment embodying the invention, various portions being broken away to contract the view.

Fig. 2 is an enlarged sectional elevation of the upper portion of the equipment shown in Fig. 1, portions being broken away to contract the view.

Fig. 3 is a sectional elevation on a still larger scale of the equipment shown in the lower portion of Fig. 1, portions being broken away to contract the view.

Fig. 4 is an enlarged sectional detail of the piston valve and cage.

Fig. 5 is an enlarged sectional detail of the piston valve seat shown in Figs. 2 and 4.

Fig. 6 is an inverted plan section on line indicated by x^a-x^a , Fig. 3.

There is provided well casing 1 having perforations 2 for the admission of oil and gas into the casing from the producing strata indicated at 3. These perforations 2 are preferably a substantial distance above the lower end of the casing and adjacent the upper end of a pump cylinder 4 which is accommodated in the downwardly expanding bore 5 of a coupling 6, said cylinder adjacent said bore 5 having a downwardly reduced portion 7 so that when it is desired to

pull the pump the cylinder will readily free itself from sand.

The coupling 6 is screw-threaded onto the pump tubing 8 which extends upward inside of the casing 1 to the surface of the earth so as to discharge oil from the well.

The coupling 6 is threaded at its lower end onto the upper end of an imperforate tubular member 9 forming an upper annular reservoir 10 adjacent and surrounding the pump cylinder 4. The lower portion 11 of the pump cylinder 4 is preferably of larger inside diameter than said upper portion so as to produce a clearance space 12 between said lower portion and a pump piston or plunger 18. When the coupling 6 is in place it seals the upper end of the chamber or reservoir 10 formed between the pump cylinder 4 and the imperforate member 9.

The lower portion 11 of the pump cylinder is provided near its upper end with perforations *a* and near its lower end with perforations *b* to allow liquid to flow from the cylinder to the reservoir 10 and from the reservoir to the cylinder. The liquid in the space 12 lubricates the friction surfaces of the piston and cylinder and yet can freely escape through the holes *a* when the piston ascends so as not to interfere with the ascending movement. The pump piston 13 is hollow and is connected by a hollow outlet coupling member 14 to a sucker rod 15 or the equivalent whereby the piston may be operated.

In the drawings the sucker rod 15 is hollow or tubular and is provided just above the outlet coupling with a perforation or perforations *c*. The lower end of the piston 13 is screw-threaded into a tubular valve cage 16 which is of somewhat less outside diameter than the inside diameter of the lower portion 11 of the cylinder 4 and which in turn is screw-threaded onto a hollow seat member 17 having a half-round valve seat 18 at the upper end of its bore. The seat 18 is adapted to be engaged by a valve ball 19 and upward movement of said valve ball is limited by lugs 20 projecting inward on the inside of the tubular cage 16. It is clear that when the piston 13 starts on its up stroke fluid inside of said piston will strike the ball 19 fairly on its top so as to force said ball onto its seat to close the inlet 18. It is clear that by having the clearance space 12 the cage 16 may be screw-threaded onto the outside of the piston 13 so that the bore of the valve cage may be a maximum in order to permit of maximum flow of oil through said cage.

Another advantage of having the clearance space 12 and the cage screw-threaded onto the outside of the piston is that the upper end of said cage forms an annular shoulder or projection 21 adapted to engage a projection or annular shoulder 22 formed by the lower end of the upper portion of the

pump cylinder so that when the piston is moved upward sufficiently far to cause engagement of the shoulders 21, 22 the cylinder 4 may be withdrawn through the coupling 6 by continued upward movement of said piston.

The lower end of the pump cylinder 4 is screw-threaded onto a tubular standing valve cage 23 having inwardly projecting lugs 24 to limit the upward movement of a valve ball 25 adapted to engage a seat 26 of a hollow seat member 27 which is inserted in the lower end of the cage 23 and which is held in place by the upper end of a discharge conduit or tail pipe 28 screw-threaded into the lower end of the valve cage 23.

The lower end of the valve cage 23 is provided with a downwardly reduced portion 29 fitting a complementarily downwardly reduced seat 30 of a hollow seat member 31 which is screw-threaded into a hollow coupling 32 that in turn is screw-threaded onto the lower end of the tubular member 9. The seat member 30 is thus supported indirectly by the pump tubing and said seat member detachably supports the valve cage 23 which in turn supports the pump cylinder.

The seat member 31 is provided with downwardly extending arms 33 adapted to engage the upper portion of the tail pipe 28 and said arms are connected together at their lower ends by a ring 34 screw-threaded into the upper end of a coupling member 35 provided with a shoulder 36 on which is seated the lower end of an imperforate tubular member 37, the upper end of said tubular member resting against an annular shoulder 38 of the coupling member 32. The tubular member 37 is held in place by reason of the seat member 31 being connected to the ring 34 by the arms 33.

The coupling 35 and tubular member 37 together with an imperforate tubular member 39, which is screw-threaded into the coupling 35, form an intermediate annular reservoir 40 surrounding the tail pipe 28. The tubular member 39 is screw-threaded at its lower end into an upper head 41 through which the tail pipe 28 extends, said head 41 closing the bottom of the reservoir 40 and the upper end of said reservoir being closed by the cage 23, seat member 31 and coupling member 32.

The head 41 may be provided with a gas or gas outlets *d* to bleed gas from the reservoir 44. The tail pipe 28 is provided just above the head 41 and adjacent the lower end of the reservoir 40 with perforations 42 to permit oil to flow from the interior of the tail pipe into the reservoir 40.

The lower portion of the tail pipe 28 is surrounded by an inner tubular member 43 spaced apart from the tail pipe to form an annular lower inner reservoir 44, the 130

upper end of said tubular member 43 being inserted inside of an annular shoulder 45 of the head 41 and the lower end of said tubular member being inserted inside of an annular shoulder 46 of a lower head 47. The annular member 43 is provided near its lower end and preferably just above the lower end of the tail pipe 28 with perforations 48 to allow the oil to flow therethrough into the lower reservoir 44. The lower end of the tail pipe 28 is spaced from the lower head 47 so that oil can flow from the lower portion of the reservoir 44 upward through the open lower end of the tail pipe 28 into said tail pipe and thence upward to the pump cylinder 4 and intermediate reservoir 40 and upper reservoir 10.

The annual shoulders 45 and 46 of the upper and lower heads respectively are screw-threaded into the upper and lower ends of an outer tubular member 49 provided near its upper end only with perforations 50 adapted to admit liquid therethrough from the casing into the annular space 51 forming a lower outer reservoir between the tubular members 43 and 49. The tubular member 49 and shoulders 45, 46 thus hold the tubular member 43 in place.

The lower head 47 is provided with outwardly projecting lugs 52 adapted to contact or nearly contact with the wall of the casing 1 to maintain the lower head 47 and parts connected therewith centrally of the casing. The head 47 closes the lower end 55 of the lower reservoirs 44, 51 and closes the upper end of a chamber 53 formed partly by the head 47 and partly by an imperforate tubular member 54 screw-threaded onto the head 47, said tubular member 54 being open at its lower end.

If for any reason the pump tubing and the parts depending therefrom should drop within the casing, it is readily understood that when the tubular member 54 enters the liquid in the well, said liquid will rise in the tubular member 54 and gradually compress whatever gas or air there is in the chamber 53 so as to gradually retard the downward motion of said pump tubing and parts in order to minimize shock on the pump tubing and parts connected therewith and thus avoid injury thereto. The head 47 and tubular member 54 thus form a buoy.

The lower head 47 may be provided internally at its closed end with intersecting ribs 55 in the form of a cross.

From the foregoing it is understood that the perforations 5, 42 and 48 are liquid-sealed when oil enters the casing perforations 2 because the level of oil in the casing will be above said perforations.

The weight of the parts suspended from the ring 34 causes the arms 33, which are normally bowed outward, to be elongated so as to tightly grip the tail pipe 28 and

thus releasably and frictionally hold said tail pipe against upward movement tending to be given it by the normal upward movement of the piston when it reciprocates in the pumping operation.

In practice, assuming that the sucker rod 15 is connected to suitable operating mechanism, not shown, the oil and gas will enter the casing 1 through the perforations 2 and will fill the reservoir 51 and will flow through the perforations 48 from said reservoir into the reservoir 44, thus filling said reservoir 44. The oil will flow from the reservoir 44 upward into the tail pipe 28 and whatever gas separates from the oil in the reservoir 44 will find exit through the gas outlets 4. The oil will ascend in the tail pipe 28 as high as the level of the perforations 2 and if there is sufficient gas pressure in the producing strata, said oil will ascend above said level and into the pump tubing. Some of the oil will flow through the perforations 42 so as to fill the intermediate reservoir 40, and some of the oil will flow through the perforations 5 into the upper reservoir 10.

If fluctuations in pressure now occur in the producing strata, because of the lowering of pressure therein due to partial relief of said pressure through the well, the reservoirs 10, 40, 44 and 51 tend to minimize fluctuations in the flow and consequently minimize disturbance of the oil. The weight of the body of oil in the reservoirs 10, 40, 44 and 51 produces pressure outward against the oil and gas in the producing strata so as to minimize the tendency of the oil and gas to flow in surges, such surges being detrimental as they produce agitation and consequent emulsification of the oil, when water is present, and said surges also lower the pressure at intervals so as to free the lighter gaseous hydrocarbon dissolved in the oil which is of great value. The surges are harmful for the further reason that they tend to carry great quantities of loosened sand, shale and other debris into the casing and thence into the pump and pump tubing, thus clogging the same.

Because of the free gas being allowed to escape from the oil in the reservoir 44 and because of the hydrostatic pressure of the oil in the various reservoirs, the oil as it ascends into the pump cylinder 4 and enters the piston 13, will be comparatively quiet so that the pump piston will effectively pump the oil and will not be merely working on a body of gas or body of foam. It is readily understood that the foaming of the oil is liable to occur, when provision is not made to prevent it, because of the comparatively sudden and great reduction in pressure of the gas and oil in the ordinary well as it leaves the producing strata and flows to or is pumped to the surface of the

earth, whatever free gas there is in the oil expanding to many times its original volume and thus agitating, churning and foaming the oil.

4. From the pump tubing 8 some of the oil passes through the perforations 9 into the sucker rod 16 and upward through said sucker rod, thus maximizing the flow of oil from the well.

10. When the piston 18 reciprocates, it is clear that the liquid in the space 19 constantly lubricates said piston so as to minimize wear of the piston and cylinder.

From the foregoing it is readily seen that, 15 in the main, there is provided a reservoir 24 having inlet perforations 48 and having gas outlets 49, and that a discharge conduit 28 extends downward into said reservoir and that the upper end of said reservoir is 20 closed, thus it is clear that the outer tubular member 49 is not absolutely essential to obtain beneficial results, though said tubular member is shown and it may at times be preferable to employ said outer tubular 25 member in order to maximize stabilization of the flow of oil and minimize disturbance thereof.

When it is desired to pull the pump cylinder and the parts attached thereto, the 30 sucker rod 16 will be drawn upward sufficiently far above the level of its normal elevated pumping position to bring about engagement of the shoulder 21 with the shoulder 22, and the sucker rod will be further 35 raised to lift the cylinder 4 so as to raise the cage 23 from the seat 20. As soon as the pump cylinder 4 starts to move upward, the downwardly expanding portion 5 and the downwardly contracted portion 7 cause the 40 cylinder 4 to readily free itself from the coupling member 6 and to free itself of any sand or the like that may have become lodged around the cylinder, so that said cylinder and the parts attached thereto can 45 be readily withdrawn upward through the pump tubing. A reverse operation of the sucker rod will again insert the pump piston, cylinder and its parts into place.

The lower portion of the pump tubing 8 50 is of enlarged diameter as at 56, said portion being sufficiently long to accommodate the pump cylinder with substantial clearance between the cylinder and said enlarged portion when the cylinder is pulled through 55 said enlarged portion so as to allow the column of oil in the pump tubing to discharge therethrough and thus prevent flooding the earth adjacent the well and prevent waste of the oil when the pump is pulled.

60. The seat member 17 as clearly shown in Fig. 3 has an enlarged portion of equal diameter with the outside of the cage 16 and the bore 57 of said seat member expands downward from the seat 18.

65. It is understood that the gas trap fe-

tures will function whether the piston be used or not; that is the gas trap will function in a flowing well to minimize agitation of the oil just the same as when a piston is employed.

I claim:

70. 1. The combination with pump tubing of a chamber connected with the lower end of said tubing and closed at its upper end and open at its lower end so as to retain air or gas when lowered into the liquid in a well.

75. 2. The combination with pump tubing of a chamber connected with the lower end of said tubing and closed at its upper end and open at its lower end so as to retain air or gas when lowered into the liquid in a well, 80 said upper end having transverse intersecting ribs to form pockets between adjacent tuba.

85. 3. In combination, means forming a reservoir having an inlet, a discharge conduit extending down into the reservoir below the inlet, and means forming a second reservoir above the first named reservoir, there being perforations in the conduit opening 80 into the second reservoir.

90. 4. In combination, means forming a reservoir having an inlet, means forming a second reservoir above the first named reservoir, pump tubing, and means forming 95 continuous communication between the first and second reservoir and between second reservoir and pump tubing.

95. 5. In combination, means forming a reservoir having an inlet, a second reservoir 100 above the first named reservoir closed at its upper end, pump tubing, and a tail pipe connected with the pump tubing and communicating with both of said reservoirs.

105. 6. In combination, a pump cylinder, a tubular imperforate plunger in said cylinder provided at its lower end with a plunger valve, an imperforated tubular member spaced from and surrounding said cylinder, the cylinder having perforations opening 110 into the space between said cylinder and imperforate tubular member below the plunger valve, and a standing valve affording communication with the lower end of the pump cylinder.

115. 7. In combination, a pump cylinder, a tubular plunger in said cylinder having a plunger valve at its lower end, an imperforate tubular member spaced from and surrounding said cylinder, the cylinder having 120 perforations opening into the space between said cylinder and imperforate tubular member, means forming a reservoir below and communicating with the pump cylinder below the plunger valve, and a standing valve 125 affording communication with the lower end of the pump cylinder.

8. In combination, a pump cylinder, a tubular plunger in the cylinder having a plunger valve at its lower end, there being iso

5 a space between a portion of said cylinder and the plunger, means forming a reservoir around the cylinder, there being perforations in the cylinder affording communication between said space and reservoir below the plunger valve, and a standing valve affording communication with the lower end of the pump cylinder.

9. In combination, a pump cylinder having an internal shoulder, a tubular plunger in the cylinder having a plunger valve at its lower end, there being a space between the plunger and the portion of the cylinder below said shoulder, means forming an external shoulder on the plunger in said space, means forming a reservoir around the cylinder, there being perforations in the cylinder affording communication between the cylinder and said reservoir below the plunger valve, and a standing valve affording communication with the lower end of the pump cylinder.

10. In combination, a pump cylinder having an internal shoulder, a plunger in the cylinder, a valve cage fastened to the lower end of the plunger and forming a shoulder on the outside of the plunger adapted when the plunger is raised above its normal pumping position to engage the first shoulder, a seat-forming member, pump tubing connected with the seat-forming member, and a standing valve cage having a seat-forming member and connected with the cylinder, said seat-forming member engaging the first named seat-forming member.

11. In combination, a pump cylinder having an internal shoulder and having perforations adjacent said shoulder, a reservoir outside of the cylinder, a plunger in the cylinder, there being a space between the plunger and the portion of the cylinder below said shoulder, and means forming an external shoulder on the plunger in said space.

12. In combination, a pump cylinder having a perforation and having a downwardly reduced portion, pump tubing, an imperforate tubing outside of the cylinder, a seat member connected with the imperforate member, a valve cage engaging the seat member and fastened to the cylinder, and a plunger in the cylinder.

13. In combination, a pump tubing, a coupling member fastened to said pump tubing and provided with an upwardly reduced bore, a cylinder having an external downwardly reduced portion adjacent the reduced bore portion, a plunger in the cylinder, a valve cage fastened to the cylinder, and a seat member engaging said valve cage and connected with the coupling member.

14. In combination, a pump cylinder, pump tubing, means detachably connecting the cylinder to the pump tubing, a plunger in the pump cylinder, and means to recipro-

cate said plunger, the lower portion of said pump tubing being of greater diameter than the upper portion of said tubing for a sufficient length to accommodate the pump cylinder with substantial clearance between the cylinder and said enlarged portion when the cylinder is pulled through said enlarged portion, and the diameter of the reduced portion of the pump tubing being but slightly greater than that of the cylinder.

15. In combination, pump tubing, an inserted deep well pump frictionally housed at the lower end of the pump tubing, said pump having a cylinder and a plunger therein, there being a space between the cylinder and plunger, a shoulder on the lower end of the plunger substantially closing the lower end of said space, there being perforations in the cylinder to supply the space with fluid for fluid packing and lubrication of the pump when the same is in operation.

16. In combination, a cylinder having an internal shoulder and having a perforation, a plunger in the cylinder, pump tubing, means detachably connecting the cylinder to the pump tubing, a valve cage screw-threaded onto the outside of the plunger and adapted to engage the shoulder to detach the cylinder when said plunger is raised for that purpose, and a reservoir surrounding the pump cylinder.

17. In combination, pump tubing, a sealing coupling at the lower end of the pump tubing, a cylinder inserted through said coupling, and a seat for the cylinder, said coupling being downwardly and outwardly tapered.

18. In combination, a reservoir having a head closing its upper end, a tail pipe extending down through said head into the reservoir, and a tubular member extending up from said head, there being inlet perforations for the reservoir and a gas outlet perforation in the head communicating with the reservoir and there being perforations in the tail pipe communicating with the interior of the tubular member.

19. In combination, well casing, pump tubing in said casing, a tubular member connected with the pump tubing and provided with an inlet, a discharge conduit connected with the pump tubing and extending into the tubular member, and a head on the lower end of the tubular member having outwardly projecting lugs adapted to center the head in the casing.

20. In combination, well casing, pump tubing in said casing, a tubular member connected with the pump tubing and provided with an inlet, a discharge conduit connected with the pump tubing and extending into the tubular member, a second tubular member, and a head closing the upper end of the second tubular member and fastened to the first named tubular member and provided

with outwardly projecting lugs adapted to center the head in the casing.

21. In combination, pump tubing, a sealing coupling 6 at the lower end of the pump tubing, a seat member below the sealing coupling, a cylinder having perforations near its upper and lower ends and seated on the seat member, a hollow plunger in the cylinder, and an imperforate tubular member connecting the coupling with the seat member, to form a chamber or reservoir outside of the cylinder.

22. In combination, pump tubing, a sealing coupling 6 at the lower end of the pump tubing, a seat member below the sealing coupling, a cylinder seated on the seat member, a hollow plunger in the cylinder, and an imperforate tubular member connecting the coupling with the seat member to form a chamber or reservoir outside of the cylinder, there being a perforation in

the cylinder to supply the chamber with fluid.

23. In combination, a reservoir having a head closing its upper end, a tail pipe extending down through said head into the reservoir, a tubular member extending up from the head, there being inlet perforations for the reservoir and a gas outlet perforation in the head communicating with the reservoir and here being a perforation in the tail pipe communicating with the interior of the tubular member, a cylinder connected with the tail pipe, and a plunger working in said cylinder. 35

Signed at Los Angeles, California, this 29th day of December, 1916.

JOHN HAHN.
